UNITED STATES PATENT OFFICE.

MORRIS D. LINNICK, OF BROOKLYN, NEW YORK.

AUTOMATIC STOP-MOTION MECHANISM FOR KNITTING MACHINES.

Application filed February 27, 1926. Serial No. 91,187.

This invention relates to improvements in automatic stop motion mechanism for knitting machines.

The primary object of the invention resides in a means for automatically stopping a knitting machine when a defect appears in the knitting of the material so that the machine will be instantly stopped to enable an operator to correct the defect. Heretofore, it has been the practice of employing an operator to watch the machine in order to be present to stop the machine as defects occur.

Another object of the invention resides in an attachment which may be applied to knitting machines now in use, without altering the present construction of the same.

A further object is to provide an automatic stop attachment for knitting machines which is simple in construction, easy to install and efficient and durable for the purpose intended.

With these and other objects in view, the invention resides in certain novel construction and combination and arrangement of parts, the essential features of which are hereinafter fully described, are particularly pointed out in the appended claims, and are illustrated in the accompanying drawing, in which:

Figure 1 is an elevational view of my improved attachment in an applied position upon a portion of a knitting machine.

Figure 2 is a vertical transverse sectional view on the line 2—2 of Figure 1.

Figure 3 is a view similar to Figure 1 but showing the position of the parts when in a shut-off position.

Figure 4 is a perspective view of the actuating member.

Figure 5 is a detail perspective view of the bell crank lever.

Figure 6 is a sectional elevational view of a modified form of my invention.

Figure 7 is a diagrammatic view of the electric circuit used in connection with the form of my invention shown in Figure 6.

Like characters of reference refer to like parts throughout the several figures of the drawing.

Referring more particularly to the drawing, the reference numeral 10 designates the frame of a knitting machine, and 11 the control box containing the conventional

form of gear 11', which when rotated, 55 throws the clutch in or out for controlling the operation of the machine.

Supported by the frame 10 is a bracket 12, one end of which is bifurcated as at 13 to provide a pair of spaced compressible 60 jaws 14 for detachably supporting an actuating member 15.

The actuating member 15 is formed of a single piece of resilient wire bent upon itself to provide a hook portion 16, which 65 is clamped between the jaws 14 by means of a clamping screw 17. The screw 17 passes freely through one of the jaws 14 but is threadedly connected with the other jaw so that by screwing the same home, the 70 jaws will be drawn together. One of the inner faces of the jaws 14 is provided with a groove 18 for receiving the bill of the hook portion to prevent vertical movement of the same. The member 15 extends forward from the bracket 12 and is bent downward at an angle as at 19, thence forward and downwardly as shown in Figures 3 and 4 of the drawings, and thence upwardly at right angle as at 20. The free end of the 75 member is bent into a hook or eye 21 for a purpose to be presently explained.

An arm 22 extends from the frame 10 and to which a bell crank lever 23 is pivotally connected as at 24'. The bell crank lever 85 comprises a relatively short branch 25, to which one end of a rack bar 26 is pivotally connected, and which rack extends into the box 11 for meshing engagement with the gear 11' and which operates the control 90 mechanism of the machine. The other branch 27 is longer than the branch 25 and has its end bent angularly to provide an ear 28 through which the threaded shank 29 of a screw eye 30 extends. The eye is held in 95 an adjusted position by lock nuts 31 co-acting with the threads on the shank and which are respectively disposed on opposite sides of the ear.

A flexible member 32 in the nature of a 100 chain has its ends respectively connected to the screw eye 30 and hook or eye 21 so as to transmit a pull from the actuating member 15 to the bell crank lever 23.

In operation, the knitted fabric 33 in its 105 passage horizontally through the machine serves to hold the actuating member 15 in an upward position under tension, as the

portion 19 of the member compresses against the knitted fabric as clearly shown in Figures 1 and 2 of the drawings.

The actuating member being firmly held by the jaws swings on a center at its point of connection with the jaws and is flexed, causing the angularly bent portion 20 to be raised at which time the rack bar 26 is in its retracted position, the same having rotated the gear to throw in the operating clutch. The machine is presumed to be in operation with the knitted fabric being fed beneath the trigger or actuating member 15. So long as the yarn passes from the spool or cone through the usual guide, to the knitting needles, the parts remain in this position, but should the yarn break due to the clogging of the thread guide or by an excess tension on the yarn, the fabric will automatically drop, as it will be appreciated that the knitted fabric is supported in the machine by the yarn. As the fabric drops, the actuating member which has previously been held under tension, is released and returns to its normal position as shown in Figure 3 of the drawing. Also, should a defect occur in the fabric, an opening will appear therein, through which the actuating member will pass to cause the operation of the device. The downward movement of the member imparts a pull to the flexible member 32 which rocks the lever 23, causing the rack bar 26 to move to an extended position, which rack bar imparts rotation to the operating gear 11' for disengaging the control clutch, which automatically stops the machine, at which time an operator will understand that a defect is present in the knitted material which must be corrected.

The above form of my invention is adapted for use on mechanically controlled knitting machines, but the same automatic stop mechanism may be used in connection with electrically controlled knitting machines, such as shown in Figures 6 and 7 of the drawings. In this form of the invention, a switch 34 is mounted upon the frame 10 of the machine, and comprises a casing 35, between the walls of which a lever 36 is pivoted as at 37. A contractile spring 38 has one end connected to the inner end of the lever and its other end to the casing 35, so as to normally tend to swing the outer end of the latter upwardly and the inner end downwardly out of engagement with a spring contact 39 supported by the casing 35. The outer end of the lever 36 is connected to one end of a link 40, while the other end of the link is connected to the eye 21 of the actuating member 15, which member is identical in construction to that shown in the preferred form. A stop member 41

extends from the casing and serves to limit the movement of the lever 36 against the action of the spring 38.

In the operation of this form, it will be seen that the knitted material 33 holds the trigger or actuating member 15 under tension, at which time the spring 38 is holding the lever 36 out of engagement with the contact 39 so that the electric circuit 42 is open, at which time the solenoid of the magnetic clutch is de-energized to permit the clutch 44 to be engaged to drive the machine. Should a defect appear in the material which releases the actuating member 15, the same will exert a pull upon the link 40, which rocks the lever 36 against the action of the spring 38 and into engagement with the contact 39, thus closing the circuit 42 which includes the battery 43 and the electro-magnetic clutch 44, thus energizing the solenoid and disengaging the clutch, which clutch when engaged imparts motion to the knitting machine from the usual driving mechanism.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

1. In combination with the gear of the control clutch of a knitting machine, a rack bar in meshing engagement therewith, a resilient member held under tension by the knitted material in its passage through the machine, and operating means for actuating said rack bar to move said gear to disengage the control clutch when the tension on said flexible member is released, said means including a bell crank lever having one of its ends pivotally connected with said rack bar, and an element connecting the other end of said bell crank lever with the free end of said resilient member.

2. An automatic stop mechanism for knitting machines including a flexible member adapted to be placed under tension by engagement with the knitted material passing through the machine, and attaching means for mounting said member on the frame of a machine, said attaching means including a bracket having spaced compressible jaws for receiving one end of said member, and a clamping screw for holding said jaws in a clamping position with said member.

In testimony whereof I have affixed my signature.

MORRIS D. LINNICK.
